DESIGN FOR A MAKE-UP TRAY

George G. Greger, Detroit, Mich.

Application August 19, 1946, Serial No. 132,631

Term of patent 14 years

(Cl. D86—10)

To all whom it may concern:

Be it known that I, George G. Greger, a citizen of the United States, residing at Detroit, in the county of Wayne and State of Michigan, have invented a new, original, and ornamental Design for a Make-up Tray, of which the following is a specification, reference being made to the accompanying drawing, forming part thereof.

Figure 1 is a top plan view of a make-up tray, showing my new design;

Figure 2 is a front elevation of the make-up tray shown in Figure 1;

Figure 3 is a right-hand end elevation of the make-up tray shown in Figure 1; and

Figure 4 is a perspective view of the make-up tray shown in Figure 1.

I claim:

The ornamental design for a make-up tray, as shown.

GEORGE G. GREGER.
